PUMP

Clarence B. Wade, Malad City, Idaho

Application August 1, 1935, Serial No. 34,269

5 Claims. (Cl. 103—102)

This invention relates to a pump adapted to be used in wells or the like and it generally aims to provide a novel, simple, and improved construction which will elevate or pump water a greater height than in existing constructions.

It is further aimed to provide a construction having a novel gasket means for anchoring the device at various elevations within a well casing.

The more specific objects and advantages will become apparent from a consideration of the description following taken in connection with accompanying drawings illustrating an operative embodiment.

In said drawings:

15 Figure 1 is a view partly in elevation and partly in section showing my improved pump within a well casing;

Figure 2 is a cross sectional view taken transversely of the pump on a plane above the cylinder thereof:

Figure 3 is an enlarged substantially central vertical sectional view taken through the pump;

Figure 4 is a cross sectional view taken on the line 4—4 of Figure 3;

25 Figure 5 is a cross sectional view taken on the line 5—5 of Figure 3;

Figure 6 is a cross sectional view taken on the line 6—6 of Figure 3;

Figure 7 is a fragmentary elevation of the pump 30 taken at a right angle to the position of Figure 1, and

Figure 8 is a detail sectional view taken on the line 8—8 of Figure 5.

Referring specifically to the drawings, the 35 pump comprises a cylinder 10 within which a rotatable shaft 11 is eccentrically disposed and on which is screwed as at 12, a rotor or impeller 13 having any suitable number of slightly inclined vanes 14. Said rotor 13 operates within an eccentric pumping chamber 15 within the cylinder 10 and which chamber tangentially communicates at 16 with a vertical discharge passageway 17, which preferably curves or inclines from the base of the cylinder toward the top thereof. The pumping 40 chamber 15 and rotor 13 therein are overlapped at the top by a wall 18 of the cylinder having a fluid inlet opening at 19 therethrough. Rising from wall 18 are a suitable number of bosses 20, for instance three, suitably spaced apart 45 as at 21 to facilitate entrance of the fluid. A suitable spider 22 has arms 23 bolted as at 24 to said bosses 20 and it also has a sleeve bearing 25 in which the shaft 11 is journaled. A nut 26 is threaded at 27 onto the tube 25 and beneath 50 the same is an expansive coil spring 28 surround-

ing the sleeve 25, and urging downward movement of a collar 29 slidably disposed on said sleeve. Collar 29 has links 30 pivoted thereto as at 31, and in turn pivoted as at 32 to overlapping sections or parts 33 constituting an expandible 5 ring 34, of channel shape in cross section and in the channel or groove of which an annular rubber or the other gasket 35 is disposed which is adapted for intimate contact with the inner wall of well casing 36 within which the device 10 is disposed as shown in Figure 1.

Between the ring 34 and upper end of the cylinder 10, a plate 37 is removably disposed, the same having an opening whereby it is telescoped over the sleeve 25 and it further has an opening 15 or slot 39 in registry with the discharge passage 17. Said plate 37 has a pair of depending lugs 41 thereon which abut lugs 42 on the arms 23, and thus prevent turning of the plate 37 relatively to the casing, to insure registry of the passages 20 17 and 39.

Across the lower end of the cylinder, a base plate 44 is disposed, which is enlarged at 45 and extends slightly into the pumping chamber 15. Plate 45 has depending legs 46 which are disposed against legs 47 depending from the cylinder, the legs 46 and 47 being detachably bolted or otherwise secured together as at 48. An entrance opening or port 49 for fluid to be pumped is provided through the plate 44, such port being elevated and communicating with the pumping chamber 15.

The nut 26 is also threaded as at 50 to a tube 51 disposed about the shaft 11. Said tube 51 depends from a coupling section 52 screw-threaded at 53 to said tube 51, and resting on the closure 54 of the casing 38. A coacting coupling or section 55 is fastened to the shaft 11, and between the sections 52 and 55 suitable ball-bearing means 56 are interposed. It will be noted that as the 40 section 55 is rigidly connected to the shaft 11, it will, upon the ball-bearings 56, support the weight of the shaft 51, and the rotor carried thereby.

Said closure 54 has an outlet pipe 57 extending therefrom for the pump for discharging fluid, and a rod 58 also slidably extends through and above the closure 54, being operatively connected to a lever 59, pivoted at 60 to the aforesaid sleeve 29.

The shaft 11 is adapted to be rotated in any suitable way and for instance by a belt suitably driven, and trained over a pulley 61 keyed thereto above the surface of the ground or closure 54.

When the pump is disposed within casings 55

such as 36, the fluid to be elevated or pumped from the casing enters the pumping chamber 15, through the ports or slots 19 and 21 and 49, and by the rotor 13, is discharged through the port 16 into the passage 17, passing rapidly and forcibly up the inclined surface thereof through the passage 39 and expansive ring 34 into the upper portion of the casing 36, rising in the latter and discharging through the pipe 57. It will be realized that during use, gasket 35 is in intimate and pump-retaining contact with the inner wall of the casing 36. However, when the pump is to be removed, applied or adjusted as to position, the element 58 is operated so as to retract the sleeve 29, links 30 and expansive ring 34 thus relieving the pressure and tension on the gasket 35 sufficiently to facilitate the movement of the pump.

Various changes may be resorted to provided they fall within the spirit and scope of the invention.

I claim as my invention:—

1. A pump of the class described having a vertical cylinder, an eccentric pumping chamber within said cylinder, a discharge passage extending generally longitudinally of the cylinder and communicating with said pumping chamber, a rotor operable in said pumping chamber, legs on said cylinder, a base plate across the cylinder having an entrance port for said pumping chamber, said base plate having legs engaging the first mentioned legs, and means securing the legs of the cylinder and base plate together.

2. A pump of the class described having a vertical cylinder, an eccentric pumping chamber within said cylinder, a discharge passage extending generally longitudinally of the cylinder and communicating with said pumping chamber, a rotor operable in said pumping chamber, a spider secured to the cylinder adjacent the top, said cylinder having a receiving port spaced from the spider, said spider having a sleeve in which the shaft of the rotor is journaled, bosses on the cylinder engaged by the spider, means securing the spider to the bosses, a plate resting on the upper end of the cylinder, and guided by said sleeve having a port in registry with said discharge passage, and coacting means between the plate and spider preventing rotation of the plate independently of the cylinder.

3. A pump of the class described having a casing, a vertical cylinder operable therein, an eccentric pumping chamber within said cylinder, a discharge passage extending generally longitudinally of the cylinder and communicating with said pumping chamber, a rotor operable in said pumping chamber, a spider secured to the

cylinder adjacent the top, said cylinder having a receiving port spaced from the spider, said spider having a sleeve in which the shaft of the rotor is journaled, bosses on the cylinder engaged by the spider, means securing the spider to the bosses, a plate resting on the upper end of the cylinder and guided by said sleeve having a port in registry with said discharge passage, coacting means between the plate and spider preventing rotation of the plate independently of the cylinder, a casing-engaging gasket above said plate, and means operatively supporting said gasket on said sleeve.

4. A pump of the class described having a casing, a vertical cylinder operable therein, an eccentric pumping chamber within said cylinder, a discharge passage extending generally longitudinally of the cylinder and communicating with said pumping chamber, a rotor operable in said pumping chamber, a spider secured to the cylinder adjacent the top, said cylinder having a receiving port spaced from the spider, said spider having a sleeve in which the shaft of the rotor is journaled, bosses on the cylinder engaged by the spider, means securing the spider to the bosses, a plate resting on the upper end of the cylinder and guided by said sleeve having a port in registry with said discharge passage, coacting means between the plate and spider preventing rotation of the plate independently of the cylinder, a casing-engaging gasket above said plate, and means operatively supporting said gasket on said sleeve comprising a collar, links pivoted to the collar, an expansive ring mounted in the gasket and to which the links are pivoted, spring means urging downward movement of the collar, and means operable to slide the collar against the tension of the spring to permit retraction of the gasket.

5. A pump of the class described having a casing, a vertical cylinder operable therein, an eccentric pumping chamber within said cylinder, a discharge passage extending generally longitudinally of the cylinder and communicating with said pumping chamber, a rotor operable in said pumping chamber, an operating shaft for the rotor, a bearing sleeve about said shaft connected to the cylinder, a plate resting on the upper end of the cylinder having a port in registry with the discharge passage of the cylinder, an expansive ring above the plate, a casing-engaging gasket mounted by said ring, a collar slidable on said sleeve, links pivoted to the sleeve and ring, spring means urging downward movement of the collar, and means operable to move the collar against the tension of the spring to permit retraction of the gasket.

CLARENCE B. WADE.
